UNITED STATES PATENT OFFICE.

RUDOLF ALIFELD, OF NEW YORK, N. Y.

WARDROBE-TRUNK.

SPECIFICATION forming part of Letters Patent No. 514,585, dated February 13, 1894.

Application filed September 15, 1893. Serial No. 485,534. (No model.)

To all whom it may concern:

Be it known that I, RUDOLF ALIFELD, of New York city, New York, have invented an Improved Wardrobe-Trunk, of which the following is a specification.

This invention relates to a wardrobe trunk, which is so constructed that the clothes therein suspended will not wrinkle, whether the trunk is open or closed.

In the accompanying drawings Figure 1 is a vertical cross section of my improved wardrobe trunk, showing it closed. Fig. 2 is a similar section showing it open and Fig. 3 a front view of Fig. 2.

The letter *a*, represents a trunk provided with the hinged cover *b*, as usual. Within this cover are arranged hooks *b'*, for suspending clothes, which may be confined in place by straps *b²*. At the front, the trunk is provided with a hinged lid *c*, which may be raised or lowered and which when raised may be locked to the cover *b*, by a lock *c'*, to close the trunk.

Back of the folding lid *c*, the trunk is provided with a short upright partition *d*, and an inclined partition *d'*, the latter extending from the top of partition *d*, toward the front of the trunk.

The space inclosed by the lid *c*, and partitions *d*, *d'*, constitutes a drawer case and contains two, more or less, drawers *e*, *e'*. Of these drawers the upper one *e'*, is provided

with inclined end pieces, which taper from the front toward the rear, so as to conform to the shape of the case beneath the inclined partition *d'*.

In use, the trunk is opened and the lid *c*, is lowered, when access to all the drawers may be had. The clothes suspended from the hooks *b'*, will extend down into the body of the trunk, back of partition *d*. When the trunk is closed the hooks *b'*, will be placed above the front end of the partition (Fig. 1) and if the straps *b²*, should become distended or loosened, the clothes will be supported by the inclined partition *d'*, up to its rear end and will thence be guided into the rear of the trunk by partition *d*. Thus no sudden break or crease can possibly be formed, which is a matter of considerable importance during travel, where trunks are usually roughly handled.

What I claim is—

A wardrobe trunk provided with a folding lid, a partition back of the lid, a hinged cover and a set of hooks within the cover which are placed above the forward end of the partition when the trunk is closed, substantially as specified.

RUDOLF ALIFELD.
